US0D1084849S

(12) **United States Design Patent** (10) Patent No.: **US D1,084,849 S**
(45) Date of Patent: ** Jul. 22, 2025

(54) **FOOD CARTON**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/991,498**

(22) Filed: **Feb. 28, 2025**

Related U.S. Application Data

(60) Division of application No. 29/722,232, filed on Jan. 28, 2020, now Pat. No. Des. 1,070,585, which is a continuation of application No. 29/644,833, filed on Apr. 20, 2018, now Pat. No. Des. 876,951.

(51) **LOC (15) Cl.** **09-03**

- (57) CLAIM**
 The ornamental design for a food carton, as shown and described.
- DESCRIPTION**
- FIG. 1 is a perspective view of a first embodiment of a food carton showing a new design;

FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof;
FIG. 7 is a bottom plan view thereof;
FIG. 8 is a perspective view of the food carton of FIG. 1 showing an alternate configuration;
FIG. 9 is a left side elevation view thereof;
FIG. 10 is a right side elevation view thereof;
FIG. 11 is a front elevation view thereof;
FIG. 12 is a rear elevation view thereof;
FIG. 13 is a top plan view thereof;
FIG. 14 is a bottom plan view thereof;
FIG. 15 is a perspective view of the food carton of FIG. 1 showing it in an open configuration;
FIG. 16 is a top plan view thereof;
FIG. 17 is a bottom plan view thereof;
FIG. 18 is another perspective view of the food carton of FIG. 15 showing an alternate configuration;
FIG. 19 is a left side elevation view thereof;
FIG. 20 is a right side elevation view thereof;
FIG. 21 is a front elevation view thereof;
FIG. 22 is a rear elevation view thereof;
FIG. 23 is a top plan view thereof;
FIG. 24 is a bottom plan view thereof;
FIG. 25 is a perspective view of the food carton of FIG. 15 showing an alternate configuration;
FIG. 26 is a left side elevation view thereof;
FIG. 27 is a right side elevation view thereof;
FIG. 28 is a front elevation view thereof;
FIG. 29 is a rear elevation view thereof;
FIG. 30 is a top plan view thereof;
FIG. 31 is a bottom plan view thereof;
FIG. 32 is a perspective view of the food carton of FIG. 25 showing a flap being removed therefrom;
FIG. 33 is a perspective view of a second embodiment of a food carton, showing the new design;
FIG. 34 is a left side elevation view thereof;
FIG. 35 is a right side elevation view thereof;

FIG. 36 is a front elevation view thereof;
FIG. 37 is a rear elevation view thereof;
FIG. 38 is a top plan view thereof;
FIG. 39 is a bottom plan view thereof;
FIG. 40 is a perspective view of the food carton of FIG. 33 showing an alternate configuration;
FIG. 41 is a left side elevation view thereof;
FIG. 42 is a right side elevation view thereof;
FIG. 43 is a front elevation view thereof;
FIG. 44 is a rear elevation view thereof;
FIG. 45 is a top plan view thereof;
FIG. 46 is a bottom plan view thereof;
FIG. 47 is a perspective view of the food carton of FIG. 33 showing it in an open configuration;
FIG. 48 is a top plan view thereof;
FIG. 49 is a bottom plan view thereof;
FIG. 50 is another perspective view of the food carton of FIG. 47 showing an alternate configuration;
FIG. 51 is a left side elevation view thereof;
FIG. 52 is a right side elevation view thereof;
FIG. 53 is a front elevation view thereof;
FIG. 54 is a rear elevation view thereof;
FIG. 55 is a top plan view thereof;
FIG. 56 is a bottom plan view thereof;
FIG. 57 is another perspective view of the food carton of FIG. 47 showing an alternate configuration;
FIG. 58 is a left side elevation view thereof;
FIG. 59 is a right side elevation view thereof;
FIG. 60 is a front elevation view thereof;
FIG. 61 is a rear elevation view thereof;
FIG. 62 is a top plan view thereof;
FIG. 63 is a bottom plan view thereof; and,
FIG. 64 is a perspective view of the food carton of FIG. 57 showing a flap being removed therefrom.

In the drawings the dotted lines are for the purpose of illustrating perforations and form part of the claimed design; and the dash-dash broken lines are for the purpose of illustrating environment only and form no part of the claimed design.
